EDWARD D. LEMMERMAN, OF CLEVELAND, OHIO

SECTIONAL CASING

Application filed April 10, 1926. Serial No. 101,115.

This invention as indicated relates to a sectional casing. More particularly it comprises a sectional structure formed principally of precast concrete units and adapted more especially for underground structures for public service such as telephone conduits, sewer, manholes, catch basins, and the like, and meter boxes for water systems. It is also particularly adaptable for the construction 10 of septic tanks and leaching cesspools for residences.

Reinforced concrete has heretofore been used in the construction of manholes and the like but in most instances such structures 15 have been built in situ and have involved the use of special forms to insure uniformity and economy of construction. This manner of procedure requires extensive equipment because of the differences in height which have 20 to be provided for, and entails much expense and loss of time owing to the fact that building operations must sometimes be carried on in places difficult of access.

The principal object of the present invention 25 is to obviate the disadvantages referred to and to provide a concrete structure formed of related units, which units may be precast above the surface of the ground and then fitted together in proper relation at the point 30 of installation. Where satisfactory conditions are found the precast units may be turned out in a plant devoted to such work and transported to the point where they are to be used. In this manner every structural 35 requirement may be met and great economy of manufacture may be provided for. Another object of the invention is to form units of several distinct types certain of which may 40 be interchangeable with others in order to provide a structure of somewhat different shape than the standard design in order to accommodate the structure for special purposes. Thus units adapted to form part of a manhole structure, may be used in connection with a different intermediate portion to 45 form a catch basin or a septic tank. Other and further objects of the invention will appear in the course of the following description. To the accomplishment of the foregoing and related ends, said invention, then,

consists of the means hereinafter fully described and particularly pointed out in the claims.

The annexed drawing and the following description set forth in detail one method 55 and several structures exemplifying my invention, such disclosed procedure and structures constituting, however, but several of various applications of the principles of my invention.

In said annexed drawings:

Fig. 1 is a central vertical sectional view showing a manhole constructed in accordance with the principles of my invention; Fig. 2 is a central vertical sectional view showing a 60 septic tank structure embodying the principles of my invention; Fig. 3 is a central vertical sectional view showing a catch basin embodying the principles of my invention; Fig. 4 is a central vertical sectional view 65 showing an intake basin constructed in accordance with the principles of my invention; Fig. 5 is a central vertical sectional view 70 showing the method of utilizing the principles of my construction to bring the manhole or other structure to a temporary grade somewhat above an established subgrade; Fig. 6 is a detail view in perspective, showing a method of producing structural units of any 75 desired height; Fig. 7 is a detailed view partly in section, showing a modified form of step and means for securing the same in position; and Fig. 8 is a perspective view partly in section, showing the method of forming the 80 field cast base.

As is clearly shown in several figures of the drawing the sectional casing comprises a series of units adapted to be placed one upon the other, preferably with interengaging end members, to form a concrete structure of chimney-like form and particularly suited for use as manholes, catch basins and the like in a sewerage system. As is shown more especially in Figs. 1 and 8 a base portion 1 is cast in the field at the point of installation 90 of the structure.

The height of the base portion is preferably such as to leave a predetermined space from the upper surface of the same to the ground to receive a predetermined number of 100

structural units. The base is preferably formed in the manner illustrated in Fig. 8 of the drawing wherein an adjustable form 2 comprising one or more sheet metal members is bent to cylindrical form and set down within the cylindrical hole formed to receive a manhole structure. The usual procedure is to excavate a cylindrical hole for the manhole, catch basin or like structure and build 10 the line of sewer to such manhole allowing the sewer pipes 3 to project into the same the required distance. The cylindrical form member is then set in between the ends of lines of sewer pipe and concrete is poured between said mold and the walls of the excavation. The concrete will thus form a cylindrical structure 4 which at its lower margins will extend over the floor of the excavation. The cylindrical mold may then be withdrawn and 20 the base of the manhole may be filled in with concrete 5 to the required degree. A trough-like portion 6 is provided in alignment with the sewer pipes to conduct the flow from one pipe to the other and the walls 7 adjacent such trough are inclined downwardly and upwardly to a point a slight distance above the top line of the sewer pipes to take care of any overflow which may be discharged into the manhole. Thus adequate space for 30 clearing the sewer pipes is afforded. The upper face of the base member is preferably provided with a groove to receive a rib formed on the under face of one of the precast sections supported thereon.

35 Immediately above the base portion, a number of precast units 8 of circular outline are positioned one above the other with their internal walls in direct alignment with the opening in the upper section of the base.

40 When a sufficient number of units of circular outline have been utilized to bring the manhole to a point closely adjacent the surface of the ground, a series of progressively tapered ring members 9 is used to reduce the diameter of the structure and permit the use 45 of a specially constructed top section 11 above the same. The tapered sections of the manhole are preferably made of slightly less thickness than the lower cylindrical sections but are of approximately twice the vertical height 50 of said lower sections. The top section is formed at its lower portion of substantially the same thickness as the adjacent tapered sections, and its inner wall may be in alignment with the inner walls of the assembled 55 tapered sections. The outer wall, however, is flared outwardly toward the top to provide a heavy upper portion 12 having a broad top face. Upon said face a flanged metal man- 60 hole ring 13 is supported and a suitable cover 14 is engaged thereover. The upper and lower edges of each of the cylindrical and tapered sections may be formed with grooves and ribs respectively which interengage with 65 complementary parts on adjacent members.

The sections in practically every instance are cemented together by suitable material.

As is clearly shown in Fig. 1 of the drawing, each of the precast sections is provided with a step 15 comprising a metal bar or strap 70 bent to provide a shoulder centrally and adjacent one end, and adapted to be engaged through an aperture in each of the sections to which it is applied. Said shoulders are adapted to bear against the inner and outer 75 walls of the unit and are offset upwardly and downwardly respectively to sustain the thrust applied to the extending tread portion. The method of attaching the steps may vary with the different units but it has been found that by leaving a hole of adequate size at the point where the step is to be positioned, and then, after placing the step in position, filling the balance of the aperture with cement the 80 steps are firmly fixed in place. In addition to the step members serving as a means of ingress or egress for the manhole, they also serve as a point of attachment for one end of a hoisting tackle, the opposite end of which is adapted to be engaged with a temporary tackle engaging element shown in the drawing as a removable eye-bolt 16 which is positioned in each section at a point opposite each step. The aperture through which the eye-bolt is inserted may be filled up with cement after 85 the unit is in place and the eye-bolt has been removed from the structure.

In addition to using the structure as a manhole it has been found that the construction is particularly suited for the building of septic tanks, a form of which is shown in Fig. 2. In such instance the base member 21 is a flat slab, built in situ, formed of substantial thickness and of circular outline and preferably provided with an annular 105 depression 22 adapted to receive a rib 23 formed on the lower edge of a precast ring member 24. The ring members are substantially identical in shape with those illustrated in connection with the manhole structure 110 heretofore described. In Fig. 2, three cylindrical ring members are disclosed, the upper one being provided with a pair of aligned openings 25, 26, within which the ends of inlet and outlet pipes 27, 28 are received and 115 firmly secured by cementing or like method. At a point intermediate of the positions of said pipes, shallow vertical grooves 29 are provided within which the ends of a baffle plate 30 preferably of wood are engaged. 120 The baffle plate prevents direct passage through the tank of the suspended solid matter delivered thereto through said inlet pipe.

Above the cylindrical portion of the tank a frusto-conical ring member 31 is provided, 125 said member having a sharp inclination and preferably being formed of greater thickness adjacent its base than at its upper edge. Upon the upper edge of said frusto-conical member a flat top member 32 of annular 130

shape is provided. A rib spaced from the outer edge of said member may be provided on the under side to engage with a groove formed on the upper face of said frusto-conical member. A closure 33, preferably comprising a flat concrete disk is placed over the opening in said top member. The upper and lower edges of each of the several structural elements may be formed with grooves and 10 ribs respectively which interengage with complementary parts on adjacent members.

When the construction is to be used as a catch basin, a field cast bottom 34 of substantial thickness is provided upon which a series 15 of cylindrical members 35 are built up, said members may have circumferential grooves and ribs as indicated to bring the same into proper register. The upper ring as shown is provided with an aperture at one side with 20 which is connected an outlet pipe 36 indicated by dotted lines which extends upwardly at an angle to a point at which it is desired to have the water level and thence substantially horizontally with sufficient inclination for 25 drainage. Above the main body portion a frusto-conical ring member 37 of sharp inclination is mounted in the manner heretofore described and above the same a top section 38 provided with a thickened upper edge 30 of a size to receive and support the metal casting 39 usually employed above a catch basin.

When the construction is to be used for an intake basin, the cylindrical rings forming 35 the lower body structure, heretofore described in connection with the catch basin, may be omitted and the frusto-conical section 41 may be mounted directly upon the field cast bottom 42. Said frusto-conical section 40 is provided at one side with an outlet 43 through which drainage may be provided for. A top section 44 of a size and shape substantially similar to the top sections heretofore described is mounted directly upon the 45 frusto-conical section, and a metal casting similar to that used upon the catch basin may be supported thereon.

Where a subgrade has been established it is usually desirable to position the permanent 50 top member 51 at that point, as is shown in Fig. 5, and to set an adjuster ring 52 of cylindrical shape and large diameter, upon the broad upper face of said top member, preferably maintained in registry by a groove 55 and rib engagement. Above the adjuster ring, or series of adjuster rings, if more than one is needed, a temporary top member 53 is provided upon which the metal closure 54 is supported.

60 The various rings are precast in standard forms and are of standard shapes and sizes. A single standard form may be employed to cast rings of various height by inserting a movable flat circular ring 61 at the desired 65 point between the inner and outer walls 62,

63, of the form, as is shown in Fig. 6. Where graduated heights of rings are available, the practice of casting the base member of the manhole structure at a fixed distance from the surface of the ground may be changed, and through the use of proper units the construction may be started at any desired point irrespective of the exact distance from the surface.

The forms for the several sections of the casing are preferably formed of metal and may comprise an annular base plate 60 provided with a pair of upstanding ribs spaced from the margins thereof against the lower edges of a pair of which cylindrical members 62, 63, are engaged to form the inner and outer walls of the molds. A similar plate (not shown) may be used to form the top of the structure. Intermediate of the walls the annular plate is formed with a depression 75 so as to provide a rib on the under side of a section formed in said mold. When the concrete is placed within the molds an air hammer may be used to insure the concrete mixture being distributed evenly throughout the area in the mold. The inner form member 62 is preferably formed in two sections having inwardly extending ears 64 and a block of wood 65 or similar spacing member may be interposed between the two sections in order 80 that when the concrete unit is completed the inner mold may be readily withdrawn therefrom by knocking out the wooden blocks and 85 withdrawing each of the sections in turn.

90 Instead of forming the step members in the manner shown in Fig. 1, it may be found desirable to apply a modified form of step member, as is shown in Fig. 7. In such case an aperture is provided through the unit 71 and the shank 72 of an offset step member 73 is 95 inserted therethrough. A washer 74 and nut 75 are then engaged upon the projecting screw-threaded end of the step-member and the off-set or angular portion of the step is then drawn against the opposite wall by 100 tightening the nut.

105 Through the use of the various structural units described, the construction of standardized concrete structures is a simple matter. In addition to economies possible 110 through quantity production of relatively small units, reinforced as desired, there is a very great economy effected through the dispensing with cumbersome molds necessitated where monolithic concrete structures are 115 made. The units may be precast at a point adjacent the work or in a central plant and shipped to the point of installation at no greater cost than for the transportation of material for forms for field cast structures. 120 The units may be easily handled by means of the tackle connections provided on each member, and the standardization of the units provides for a minimum number of forms with 125 adequate selection of parts to meet the re- 130

quirements of a large number of structures for special purposes.

While the invention has been described as applied to the building of structures used with a sewer system, it is to be understood that the invention is in no way to be limited to such use and may be applied to many other uses such as the construction of manholes for telephone conduit systems or to meter boxes for water systems.

Other forms may be employed embodying the features of my invention instead of those herein explained, change being made in the form or construction, provided the elements stated by any of the following claims or the equivalent of such stated elements be employed.

I therefore particularly point out and distinctly claim as my invention:

1. In an article of the character described, the combination of a field-cast base provided with an upstanding flange portion open at opposite sides to provide an inlet and outlet aperture, said flange portion being provided with a groove on its upper edge, a series of precast circular sections having ribs and grooves on their respective edges and adapted to interengage with each other, the rib on the lowermost of said sections being seated in the groove in said flanged base, a series of precast tapered sections provided with grooves and ribs on opposite edges and interengaged with each other, the ribs on the lowermost of said edges being received in the grooves on the precast circular sections, and a precast top section formed with a rib on its lower edge being adapted to interengage with the groove upon the uppermost of said tapered sections, said top section being thickened adjacent its upper edge to provide a supporting surface for a closure.

2. In an article of the character described, the combination of a field-cast base provided with an upstanding flange portion, said flange portion being provided with a circumferential interlocking element at its upper edge, a series of precast circular sections and precast tapered sections having circumferential interlocking elements on their respective edges and adapted to interengage with each other, the element on the lowermost of said sections being engaged with the complementary element on said flanged base, and a precast top section formed with a circumferential interlocking element on its lower edge adapted to interengage with the complementary element upon the uppermost tapered section, said top section being thickened adjacent its upper edge to provide a supporting surface for a closure.

Signed by me this 3rd day of April, 1926.
EDWARD D. LEMMERMAN.
